F. SATTERSTROM.
ROTATABLE ELECTROMAGNETIC CLUTCH.
APPLICATION FILED MAR. 20, 1917.

Patented July 16, 1918.

UNITED STATES PATENT OFFICE.

FERDINAND SATTERSTROM, OF HASTINGS, MINNESOTA, ASSIGNOR TO MAGNETIC POWER TRANSMITTER COMPANY, OF FARIBAULT, MINNESOTA, A CORPORATION OF MINNESOTA.

ROTATABLE ELECTROMAGNETIC CLUTCH.

1,273,003.

Specification of Letters Patent. Patented July 16, 1918.

Application filed March 20, 1917. Serial No. 155,974.

To all whom it may concern:

Be it known that I, FERDINAND SATTERSTROM, a citizen of the United States, resident of Hastings, county of Dakota, State of Minnesota, have invented certain new and useful Improvements in Rotatable Electromagnetic Clutches, of which the following is a specification.

The object of my invention is to provide a magnetically controlled clutch device through which power may be easily and quickly transmitted intermittently to an operating mechanism which can be readily adapted for a variety of purposes.

15 A further object is to provide a mechanism of the class described which is capable of performing its functions without the jar or shock frequently incidental to the starting and stoppage of clutch control devices.

20 A further object is to provide a mechanism capable of operating at high speed and with great accuracy.

Other objects of the invention will appear from the following detailed description.

25 The invention consists generally in various constructions and combinations, all as hereinafter described and particularly pointed out in the claims.

In the accompanying drawings forming part of this specification,

Figure 1 is a front view of the magnetic clutch, shown partly in section.

Fig. 2 is an end view of the same.

Fig. 3 is a detail cross sectional view of 35 the opposite end from that shown in Fig. 2.

Fig. 4 is another detail sectional view.

Fig. 5 is a rear view of same.

In the drawing, 2 represents a base upon which I mount a suitable electric motor 3. 40 The motor is provided with a shaft 4 having secured thereon a soft metal sleeve or armature 5 rotating therewith. Said motor is connected with a suitable source of electric energy by suitable conductors (not shown).

45 While I prefer to employ an electric motor for rotating the shaft 4 I do not limit myself thereto as any suitable motor that may be continuously operated at a uniform speed to continuously rotate a shaft may be 50 employed.

Arranged above the shaft 4 and parallel and in close proximity thereto is a rotatable magnet 6, and when this magnet is energized

it moves against and is clutched to the rotating shaft armature, and is caused to rotate therewith to the extent of one complete revolution. The magnet is mounted upon a freely rotating shaft 7 which is provided with a gear 7 or any other suitable means for transmitting power from said shaft 7. 60 As here shown the base 2 is provided with a bracket 8 having standards 9 and 10. Pivoted to the upper ends of these standards is a bar 11 which carries the laterally projecting heads 12. These heads are circular in 65 form and they provide bearings for the shaft 7. The magnet 6 is preferably formed of a metal spool 13, mounted upon the shaft 7, and having a suitable conducting coil 14 wound thereon. The bar 11 is provided 70 with a tail-piece 15 to which a spring 16 is connected. This spring has its opposite end connected to the standard 9 and tends to rock the bar 11 on its pivot and thereby to raise the magnet from the shaft armature 75 5. The disk 17 on the end of the shaft 7 has a notch 18 in its periphery and a pivoted dog 19 is provided having a lug 20 adapted to engage said recess 18. To insure the lug 20 engaging the recess 18 and not jumping 80 over the same, I prefer to cut down the edge of the disk on the side of the notch 18 over which the lug 20 passes as it enters said notch. A spring 21 is connected to the dog 19 and to a pin 22. This pin tends to 85 hold the dog snugly against the edge of the crank disk so as to insure the lug 20 entering the notch in the edge of the crank disk. For increasing and decreasing the tensions of the spring 21, I provide preferably special means hereinafter described.

I also provide on the shaft 7 a cam 23, the edge of which is in the form of a radially extending lug. A block 24 is pivoted on a suitable support and this block has an upward extension 25, which projects into the plane of the cam 23, and is engaged by said cam, which action rocks the block 24 upon its pivotal support. The block 24 carries the insulated contact springs 26 and 27 as 95 shown in Fig. 3 of the drawings. An insulating block 28 is mounted on a bar 11 and carries a contact spring 29 that is in contact with the insulated ring 30 on one end of the rotatable magnet 6 (see Figs. 1 100 and 3). This ring is connected to the con-

ductor 14 of the magnet. The other end of said conductor is grounded to the spool 13. The insulating block 28 has preferably a recess extending through it with a contact 5 screw 31, projecting through one wall of the recess, and a contact point 32 on the opposite wall is connected with the spring 29. The contact springs 26 and 27 project into said recess in the block 28 and stand opposite the contact screw 31 and point 32, as clearly shown in Fig. 3. When the end of the projection 25 on the block 24 is engaged by the cam 23 the block 24 is rocked and moves the contact spring 26 into engagement with the 10 end of the contact screw 31 as illustrated in Fig. 4. When, however, the end of the projection on the block 24 is not engaged by the cam 23 the end of the contact spring 26 is out of contact with the end of the screw 15 31, and the end of the contact spring 27 is in engagement with the contact point 32 on the spring 29, as illustrated in Fig. 2. The spring 33 is mounted on the bracket 8, and this spring engages a heel or lug 34, 20 provided in the block 24, thereby tending to rock the block 24 so as to hold the contact spring 27 at all times in engagement with the contact point 32, while permitting it to be moved away when the cam projection 23 25 passes the upwardly extending projection on the block 24.

Secured to the block 11 is a plate 35 carrying a pair of small hangers 36, and an electromagnet 37 is mounted in these hangers 30 (see Fig. 5). An armature 38 for this magnet is secured upon a small rock shaft 39. The dog 19 is loosely mounted upon this shaft 39 and a pin 22 is inserted in the shaft 39 and extends through a slot in the 35 hub of the dog 19 (see Fig. 2). To the end of the pin 22 is connected a spring 21 which is also connected to the dog 19. The lug 20 on the dog 19 rides on the edge of the cam disk 17, while the current is passing 40 through the rotatable magnet. When the projection 23 engages the upwardly extending projection 25 on the block 24 the shaft 39 is rocked to bring the armature 38 closer to the magnet 37, also putting the spring 45 21 under tension, and also breaking the current through the rotatable magnet and as the spring 26 engages the end of the contact screw 31 the current is passed through the magnet 37 by means of the conductor 40. 50 This causes the armature 38 to be drawn toward the magnet 37, rocking the shaft 39 farther upon its axis and moving the pin 22 with said shaft, thereby further increasing the tension of the spring 21. This occurs just the instant before the projection 55 20 on the dog 19 comes opposite the recess 18 in the edge of the cam disk 17, thereby causing said lug to be quickly and firmly drawn into said recess and positively stopping movement of the magnet. The posi-

tion of the cam 23 in relation to the disk 17 can be changed so as to allow proper time for the momentum of the magnet 6 and the notch in its disk to be engaged by the dog 19 and stopped. 70

The purpose of this is to prevent any over-run of the rotating magnet after the circuit is broken and the magnet has been demagnetized. As the magnet rotates very rapidly it might slightly over-run if this 75 positive stop was not provided. 80

Circuit for the magnet clutch.

By referring to Fig. 3 of the drawings the path of the electric current for energizing the rotating magnet and the magnet which applies the positive stop to said rotating magnet may be readily traced. As here shown conductor 41 extends from the battery 42 to the insulated block 43, secured upon the rocking block 24 and electrically connected with the contact springs 26 and 27. Normally the spring 27 is in contact with the contact point 32 on the contact spring 29, so that when the switch 44 is 90 either manually or automatically closed the rotatable magnet is energized, the path of the current being in this instance from the battery 42 through the conductor 41, the spring 27 and the spring 29 to the insulated 95 ring 30, thence to the coils of the magnet to a ground conductor 45. As the rotatable magnet approaches the end of a single revolution the contact spring 26 is moved against the end of the contact screw 31, and the 100 spring 27 is moved away from the contact point 32. The current is now switched off from the rotatable magnet and through the small magnet 37. As this magnet is energized its armature 38 is drawn toward it 105 and the shaft 39 is rocked thereby insuring the engagement of the lug 20 on the dog 19 with the recess 18 in the disk 17, and positively stopping the rotatable magnet at the right point. The circuit for this magnet 37 110 is through battery 42, spring 26, contact screw 31, and conductor 40 to magnet, thence to the ground conductor 45 and switch 44 to battery. When the switch 44 is opened the circuit, through the magnet 37 is broken 115 and the parts are returned to their normal position ready for the next operation. 120

As the shaft 39 is rocked back to its normal position the tension on the spring 21 is released and the dog 19 is restored to its 120 normal position indicated in Fig. 2, with its lug 20 out of engagement with the recess 18 in the disk 17. The rotatable armature, therefore, is free to move again as soon as a current is passed through its coils, and 125 it is again energized and clutched to the constantly running shaft armature.

It will be seen, therefore, that each time the switch is closed the rotatable magnet will be energized and clutched to the con- 130

tinuously rotating shaft armature thereby making one revolution, and the rotation of said magnet be further transmitted through its gear 7', or any other suitable means, such as a crank. If preferred I may not break the circuit in the magnet 37 until prior to starting again. This will hold the dog 19 in engagement with the disk 17, and keep the magnet 6 locked, but by throwing the switch off and on again the aforesaid circuit will be broken, the magnet 6 released and the circuit made through said magnet and caused to clutch the ring armature 5 and revolve therewith to the extent of one revolution when its current will be broken and the circuit again made through the magnet 37 and spring 36 to lock and hold the magnet 6 until the next operation of the switch.

I do not limit myself to the details of construction herein shown and described, as the same may be varied in many particulars without departing from my invention.

I claim as my invention:

1. A device of the class described, comprising a relatively revoluble magnet and armature, said magnet being movable toward and from the armature and having an electric circuit and a circuit maker and breaker, a driven member operated by said magnet, and means for operating said circuit maker and breaker.

2. A device of the class described, comprising, in combination a revoluble armature, means for revolving said armature, a revoluble magnet mounted in proximity to said armature and movable toward and from the armature, means for energizing and de-energizing said magnet, whereby the same when energized will be revolved with said

armature, and a driven member connected with said magnet to be driven therefrom.

3. A device of the class described comprising a driving shaft, an armature mounted thereon, an electromagnet adjacent to said armature mounted for relative revolution, an electric circuit for energizing said magnet, a driven member connected with said magnet, and a device for alternately releasing and locking said magnet.

4. A device of the class described comprising a driving shaft, a cylindrical armature therefor, an electromagnet, said magnet and armature mounted for relative revolution, an electric circuit for said magnet, a circuit closer therefor, a driven member connected with said magnet and a device for releasing and stopping said magnet.

5. A device of the class described comprising a driving shaft, a cylindrical armature therefor, an electromagnet mounted for attraction to said armature to be revolved thereby, an electric circuit for said magnet, a circuit closer therefor, a member driven from said magnet and a device for releasing and stopping said magnet.

6. A device of the class described, comprising a revolving magnet and an armature for revolving the same, an electric circuit and circuit closer for said magnet, a member having a driving connection with said magnet, a locking means for said magnet having a trip for releasing said magnet, and a magnet having a circuit and an armature connected with said locking means for checking said revolving magnet at the end of each revolution.

In witness whereof, I have hereunto set my hand this 12th day of March, 1917.

FERDINAND SATTERSTROM.
